UNITED STATES PATENT OFFICE.

LEWIS H. FALLEY, OF KANSAS CITY, MISSOURI, ASSIGNOR TO M. H. FALLEY, OF KANSAS CITY, MISSOURI.

BAFFLE STRUCTURE FOR DREDGING OPERATIONS.

Application filed October 23, 1922. Serial No. 596,337.

To all whom it may concern:

Be it known that I, LEWIS H. FALLEY, a citizen of the United States, and resident of Kansas City, county of Jackson, State of Missouri, have invented a certain new and useful Improvement in Baffle Structures for Dredging Operations, of which the following is a complete specification.

The present invention relates to apparatus 10 for use in dredging or analogous operations in the beds and banks of rivers or waterways, and aims to provide an improved construction of this general character which is adapted for efficient operation 15 in shifting the material of such beds or banks, or for protecting the same, by a modification of the movement of the water-currents into which the apparatus is introduced.

20 For this purpose I have devised an improved water deflecting or baffling means designed to effect the necessary modification of the water movement for securing such shifting or deposit of the material to be 25 acted upon as is required, together with an improved form of supporting means whereby the baffle structure may be not only properly supported and conveniently adjusted into its most effective working position, but also shifted from point to point as 30 the work progresses.

With this general object in view, as well as minor objects as will hereinafter appear, the invention will now be described by reference to the accompanying drawings, illustrating practical forms of embodiment of the same, after which those features deemed to be novel will be particularly set forth and claimed.

40 In the drawings Figure 1 is an elevation showing the improved apparatus supported by a boat and in working relation to the bed of a stream;

Figure 2 is a plan view of the same;

45 Figure 3 is a section taken on the line III—III of Figure 2;

Figure 4 is a perspective view of a modified form of the apparatus;

50 Figure 5 is an enlarged detail sectional view of the same; and

Figure 6 is a similar view showing a modified form of one of the baffle elements.

Referring now to said drawings in detail, and more particularly to Figures 1 to 3, these illustrate the invention in the

form of a pair of forwardly converging baffle members 10,—that is, forwardly with reference to the direction of the current as indicated by the arrows in Figure 1, each of the baffle members 10 comprising an upper row of baffle elements or blades 11, and a lower row of baffle blades 12. The particular size, pitch and contour of these blades are immaterial, as these factors would of course depend upon the conditions of use, the arrangement illustrated being similar to that shown in my copending applications Serial No. 562,142, filed May 19, 1922, and Serial No. 575,693, filed July 17, 1922. In this arrangement, the blades 11 and 12 are bent and also slightly twisted in opposite directions, so that in intercepting a current flowing in the direction indicated the water will be deflected downward by the lower blades 12, and the two sets of blades 12 will operate to spread the current flow in opposite directions as indicated by the arrows in Figure 2. The rear ends of the members 10 are connected by a cross brace 13, and also formed with rearwardly projecting arms 14 adapted to be secured by bolts 15 to a pair of supporting arms 16 provided with a series of bolt openings 17 for adjustable connection with the arms 14. The arms 16 are elbow-shaped 80 for supporting the baffle structure in depending relation to the end of a boat 18, to the opposite sides of which are secured trunnion blocks 19 for pivotally mounting the upper ends of the arms 16, the latter being provided with a plurality of openings 20 for adjustable connection with the blocks 19. By means of this supporting structure, the baffle members may be adjusted both vertically and horizontally with 95 relation to the hull of the boat, into the required operative position. At their forward connected ends, said baffle members 10 are attached to a cable 21 operating over a roller 22 at the upper end of a staff 23 carried by the boat, on which may also be located a suitable winch device 24 for the purpose of operating the cable for lowering or raising the baffle structure into and 100 out of operative position, in an obvious 105 manner. To the forward connected ends of the baffle members is also attached a shoe 25 curving to a level below that of the lower ends of the blades 12 for affording protection to the latter against injury from the 110

bed of the stream in case the device is moved while in operative position.

Supported within the baffle structure is a hood or canopy 26 open at its rear end to the water flow and sloping forwardly toward the meeting point of the baffle members 10, the lower edge of the hood coinciding approximately with the middle line of said baffle members and the rear end of 10 the hood projecting slightly above the upper blades 11.

On positioning the above apparatus in such a manner that the current of the water-way will be received within the open or rear end of the apparatus, as indicated in Figure 1, the main body of the current will be deflected downward by the hood or canopy 26 and intercepted by the lower baffle blades 12. These blades will divide the water into 20 a multiplicity of minor or secondary currents moving downward and outward with a spiral or twisting motion and against the material composing the bed of the stream, causing a loosening and digging effect. The provision of the hood 26 accentuates the movement of the waterflow in the direction of the lower blades and thereby promotes this material loosening action. That portion of the waterflow which is intercepted 25 by the upper blades 11 is deflected upwardly and outwardly, which is the proper action for facilitating the outward sweep of the lower strata of the water by the action of the lower blades. The combined action of the baffle members is to loosen the material and, by the outwardly deflected motion of the divided or secondary currents produced by the baffle blades, divert the material to a position out to one side or the 30 other of the baffle structure, which thus operates to sluice a path through the bed of the stream, or to break down a bar or other obstruction which may be subjected to the 35 operation of the device.

Referring now to Figures 4 and 5, these illustrate a modification making use of a triangular frame 30 carrying a single group of baffle blades comprising the upper row of blades 11' and lower row of blades 12' 40 along one side of the frame. This frame 30 may be of hollow construction, as shown, for the purpose of strength and lightness, and also given greater buoyancy by means of a sealed vacuum. The projecting arms 31 45 at the rear of the frame 30 are provided with pins 32 for securing it to the supporting arms 16 in lieu of the baffle structure already described, and the front corner of the frame is provided with a projection 33 50 for the attachment of the cable 21. In place of a second group of baffle blades, as in the first form of construction, the other side of the frame 30 in this modification is provided with a plain facing of suitable sheet 55 material forming a vertical wall 34, to the

inner face of which is secured a pair of angle strips 35 converging toward the front end of said wall. To either of these strips 35 is adapted to be secured one side of a flat hood or canopy plate 36 in inclined position with its other side edge resting on the other side of the frame 30 at the base of the upper baffle blades 11'. For accentuating the baffle action of the blades, a pair of water pipes 37 may be mounted above and 75 below that side of the frame 30 carrying the baffle blades, with jet pipes 38 projecting in the direction of each blade, suitable water connections (not shown) being designed to be attached to either of said pipes 37 for supplying water thereto under pressure. The two sets of water jets and interchangeability of the plate 36 with reference to the supporting strips 35, enables this form of the device to be reversed, so that the discharge from the baffle blades will take place either to the right or to the left. This form of the construction is especially adapted for working in close to the shore or along docks or landings where it is desired to discharge 80 material from one side only.

Referring to Figure 6, the ends of the baffle blades may be notched or forked as indicated at 40, for adapting them to exert a more positive breaking up effect upon such 95 material as they may come in contact with, and thus render it more susceptible to the action of the current. The blades may be moreover reinforced by means of bars or strips 41 connecting and bracing the blades 100 of each row.

It is thus apparent that I have devised an efficient and practical construction for carrying out operations of the character indicated. In addition to the uses stated, it 105 may also be pointed out that the apparatus is useful for protecting the banks of rivers and streams, as by preventing the formation of sand bars at or near any water intake; for making fill-ins of such material; and for 110 either digging canals or other waterways, or for cleaning the beds of the same by sluicing. The device can be made in any desired size and for operation in a permanent position, as on piling and supported by cables 115 or other means. In smaller sizes, the device may be drawn through the waterway by horsepower, tractor, or the like, but as herein illustrated the apparatus is designed primarily to be operated from a boat as the 120 most desirable and efficient method of use, and while I have described what appears to be the preferred form of embodiment of the invention, I desire to reserve the right to make such changes or modifications as may 125 fairly fall within the scope of the appended claims.

What I claim is:

1. A baffle structure adapted to be submerged in the path of a water current, and 130

comprising a plurality of baffle fingers presented at an angle to the current and operative to break up and deflect the current at an angle to its normal path, and a hood member having a surface presented at an angle to the current and in position to divert the current into the direction of said baffle fingers.

2. A baffle structure adapted to be submerged in the path of a water current, and comprising a pair of converging baffle members each carrying a row of baffle fingers at an angle to the current and operative to break up and deflect the current at an angle to its normal path, and a hood member positioned between said baffle members at an angle to the current and in a position to divert the same downwardly and outwardly in the direction of both sets of baffle fingers.
3. A baffle structure adapted to be submerged in the path of a water current, a supporting structure including a pair of pivoted and vertically adjustable arms, said baffle structure being provided with a connection to said arms permitting adjustment of the position of said baffle structure horizontally with reference to said supporting structure, and means for raising and lowering said baffle structure about the pivot axes of said supporting structure.

4. A baffle structure adapted to be submerged in the path of a water current and comprising a pair of baffle members each carrying a row of baffle fingers at an angle to the current and operative to break up and deflect the current at an angle to its normal path, and a hood member positioned at an angle to the current and in a position to divert the same downwardly and outwardly in the direction of both sets of baffle fingers.

5. A baffle structure adapted to be submerged in the path of a water current and comprising a baffle member having an upper row and a lower row of baffle fingers, both of said rows being arranged at an angle to the current and adapted to break up and deflect the current at an angle to its normal path, and a hood member arranged at a forward

inclination to the direction of the current, the rear end of said hood member being somewhat higher than the upper ends of the upper baffle fingers and one side of said hood member extending along the middle line of said baffle member between said upper and lower rows of fingers.

6. A baffle structure adapted to be submerged in the path of a water current, and comprising a pair of converging baffle members each having an upper and a lower row of baffle fingers at an angle to the current and operative to break up and deflect the current at an angle to its normal path, and a hood member positioned between said baffle members at a forward inclination to the direction of the current, the rear end of said hood member being somewhat higher than the upper ends of the upper baffle fingers and the sides of said hood member extending along the middle lines of said baffle members between said upper and lower rows of fingers.

7. In combination with a boat, a baffle structure adapted to be submerged in the path of a water current and comprising a pair of converging baffle members each having an upper and a lower row of baffle fingers at an angle to the current and operative to break up and deflect the current at an angle to its normal path, means between said baffle members for deflecting the main body of the water current in the direction of said lower rows of baffle fingers, and means for lowering and raising said baffle structure into and out of operative position.

8. A baffle structure adapted to be submerged in the path of a water current and comprising a plurality of baffle fingers presented at an angle to the current and operative to break up and deflect the current at an angle to its normal path, and a protective shoe carried by one end of said baffle structure in position for shielding the free ends of said baffle fingers.

In witness whereof I hereunto affix my signature.

LEWIS H. FALLEY.
